UNITED STATES PATENT OFFICE.

FRED PEMBERTON THOMPSON, OF FREDERICTON, NEW BRUNSWICK,
CANADA.

SLEIGH-SHAFTS.

SPECIFICATION forming part of Letters Patent No. 281,162, dated July 10, 1883.

Application filed February 16, 1883. (No model.)

To all whom it may concern:

Be it known that I, FRED P. THOMPSON, of 5
Fredericton, in the county of York, Province
of New Brunswick, and Dominion of Canada,
have invented certain new and useful Improve-
ments in Sleigh-Shafts; and I do hereby declare
that the following is a full, clear, and exact de-
scription of the invention, which will enable
others skilled in the art to which it appertains
10 to make and use the same, reference being had
to the accompanying drawings, which form a
part of this specification, and in which—

Figure 1 is a top view of my improved
shifting sleigh-shaft when closed. Fig. 2 is a
15 similar view of the same when extended.
Fig. 3 is an end view of the same, and Figs.
4 and 5 are top views of a modification of the
same.

Similar letters of reference indicate corre-
20 sponding parts in all the figures.

My invention has relation to sleigh-shafts;
and it consists in the improved construction
and combination of parts of a set of sleigh-
shafts which may be shifted to one side when
25 desired, allowing the horse to run in the track
made by one of the horses of a double team and
keeping the sleigh in the track, as will here-
inafter be more fully described and claimed.

Upon roads where double teams are used it
30 is usual to have the shafts of a sleigh for a sin-
gle horse placed somewhat to one side of the
sleigh, enabling the horse to travel in the
track made by one of the horses of a double
team, and at the same time keep the sleigh run-
35 ning in the track made by the preceding two-
horse sleigh; but by that construction of shafts
the horse is always obliged to be somewhat to
the side from the sleigh, which, if it after-
ward becomes necessary to drive the horse in
40 the middle of the track, throws the sleigh out
of the made track. To obviate this, and to
enable the shafts to be adjusted either straight
in front of the sleigh or to the side of it, I cut the
shafts in two parts at the place where the cross-
45 bar generally is, and connect the cut ends by
two cross-bars. By reference to the accom-
panying drawings the manner will be plainly
seen, the letters A A indicating the inner
parts of the shafts, which are fastened to the

sleigh; B, the cross-bar connecting them; C C, 50
the outer parts, and D the cross-bar connect-
ing them, upon which the single-tree E is piv-
oted. The ends of the outer parts of the
shafts and the ends of the inner parts are be-
velled or tongued and grooved correspondingly, 55
so as to connect them more perfectly when
closed. Two sets of metal arms, F, are pivoted
in pairs upon the upper and under sides of the
cross-bar B at one end and of D at the other
end, in such a manner that when the cross- 60
bars are brought close together the outer and
inner portions of the shafts are in line, while
as they are separated the outer portion of the
shafts will be brought to one side. The inner
ends of the arms F have two projections, G and 65
H, the facing edges of which have notches I
and J, which engage sliding latches K and L
upon the cross-bars. These latches consist of
two slotted plates, M, sliding upon pins N up-
on the front side of cross-bar D and rear side 70
of cross-bar B, and are connected by a rod, O.
These plates M have each two cross-arms or
lugs projecting above and below the side of
the cross-bar, and engage the notches I and J.

Springs P are fastened upon the shafts at 75
one end and bear with their free ends against
the latches nearest to them, which operate the
other latches through rods O, so that they will
snap into the notches I and J, the latches L
engaging notches I when the shafts are closed, 80
while the latches K engage notches J when the
shafts are extended. It will be seen that in
this manner the shafts may be shifted in a mo-
ment of time, and that when shifting the shafts
to the side they are moved forward sufficiently 85
to obviate the necessity of lengthening the
traces to bring the horse far enough from the
sleigh, so that the runner shall not interfere
with the action of the horse.

In Figs. 4 and 5 a modification is shown, in 90
which the cross-bars slide upon each other and
are tongued and grooved to keep them in true
position to each other, while two set-screws,
Q, projecting into two metallic stirrups or
bails clasping the two cross-bars, allow the 95
shafts to be slid to one side when they are
loosened and hold them firmly together when
fastened.

Having thus described my invention, I claim and desire to secure by Letters Patent of the United States—

The combination of the inner portions, A, of the shafts, connected by cross-bar B, having sliding latches K K, connected by rod O and operated by spring P, outer portions, C, of the shafts, connected by cross-bar D, having sliding latches L, connected by rod O and operated by spring P, and arms F, having projec-

tions G and H, notches I and J, and pivoted upon the cross-bars, as and for the purpose shown and set forth.

In testimony that I claim the foregoing as my own I have hereunto affixed my signature 15 in presence of two witnesses.

FRED PEMBERTON THOMPSON.
